UNITED STATES PATENT OFFICE.

RICHARD KITSON, OF LOWELL, MASSACHUSETTS.

COTTON-OPENER.

SPECIFICATION forming part of Letters Patent No. 245,923, dated August 16, 1881.

Application filed May 21, 1880. (No model.)

To all whom it may concern:

Be it known that I, RICHARD KITSON, of Lowell, Massachusetts, have invented a new and useful Improvement in Cotton-Openers, of which the following is a specification.

My invention relates to machines designed to take the cotton or other fiber received in bunches or masses and open it out to form a lap therefrom.

The object of my improvement is to deliver to the beater of such a machine an even and regular quantity of fiber, and to provide such a feed mechanism as will adapt the machine to open fibers matted together by coloring processes and fibers not hitherto possible to practically operate upon in the opener.

In the accompanying drawings, in which similar letters indicate like parts, Figure 1 is a side elevation, partly in section, of a machine embodying my improvements. Fig. 2 is an end elevation of the lever evener mechanism seen in Fig. 1. Fig. 3 is a side elevation.

A is the frame of the machine. C C are evener-levers; c, the feed-roll; H, a worm-wheel placed upon the shaft of roll c; h, a worm engaging with the wheel H and attached to the top of the shaft of the cone I. j is a belt, through which motion is communicated to the cone I from the cone J. J is a cone, driven with a regular rotary movement from any convenient mill-shaft by a belt (not shown) which passes over the pulley upon the lower end of its shaft.

l l are belt-shippers, whose belt-forks raise or lower the belt upon the cones with each movement given them. These belt-shippers are made to move together by having upon their shorter arms toothed arc-pieces which engage the one with the other.

m n is a bell-crank lever, the arm m of which is connected to one of the belt-shippers, and the arm n is connected by the bar o to one of the wedge-ended connecting-rods lifted by the levers C. All these rods bear against the one to which the bar o is connected through one another and small spreader-pieces placed between them.

All these parts are constructed, connected, and operated substantially in the manner described in Patent No. 52,008, issued January 9, 1866.

When any sheet of cotton is fed between the

feed-roll c and the levers C the sheet will be firmly pressed against the roll c, and any irregularity in the sheet will cause a movement of one or more of the levers, and a corresponding movement through the connecting parts is communicated to the belt-shippers, by which the belt is moved up or down upon the cones, and a corresponding change made in the speed with which the cone I, worm h, wheel H, and feed-roll c are driven, in the same manner as described in said patent.

B is a gage-box, into which the cotton is fed, either by hand or by a feed-apron, upon which it is placed.

a' a' are grasping-rolls, which take the cotton as it is fed into the box and hold it while it is struck by the fingers a² upon the breaker shaft or cylinder a. As the fibers are separated by the action of the fingers and rolls they fall upon the apron f, which carries them under the press-roll e and out of the box in the form of a sheet, which passes between the press-rolls k k, which are borne upon by springs acting upon their journals. All these parts, which are inclosed within the gage-box, except the rolls k k, operate in substantially the same manner as does the mechanism described in Patent No. 222,410, issued to me December 9, 1879.

D is a forwarding-roll, placed between the press-rolls k and the feed-roll c and provided with spikes or teeth of considerable length. This forwarding-roll is driven by a gear placed upon the shaft of roll c, marked n' in Fig. 2 and indicated by dotted lines in Fig. 1. The sheet of cotton, passing out from the gage-box between the press-rolls k k, is rendered quite compact by them, after which it passes between the forwarding-roll D and the evener-levers C, and, being pushed forward and prevented from expanding by the toothed or spiked roll D, passes under the roll c. The cotton or fiber passing between the pressure-rollers k in a sheet has some parts thicker than others, and when it has been previously matted by the operation of coloring or dyeing may have greater density in one part than another when of the same thickness, and as the feed-roll c must be small to bring the beater near the nip of the roll so that it can act upon the fiber while held by the roll, and as the flutings on that roll cannot be very deep without injuriously affecting its action upon the evener-levers and its hold

upon the cotton being fed to the beater, it follows that when any dense masses pass between the rolls *k*, or when rough fibers like wool are fed onto the levers by those rolls, the feed-roll 5 *c*, when not aided by the spike-roll *D*, fails to grasp the entire sheet, or the upper and looser parts thereof, as they expand after leaving the rolls *k*, and the lap is torn, and greater unevenness in the feed to beater is caused; but 10 with my forwarding-roll *D* interposed, it being provided with spikes or teeth of considerable length, which will enter among the fibers and practically extend entirely through the sheet of cotton being fed to the feed-roll, it 15 will, while forwarding the sheet to the feed-roll, compress the looser parts of it, and, being close to the feed-roll *c*, will deliver to it all of the sheet sufficiently compact to be taken or nipped by it and carried forward over the even- 20 er-levers to the beater.

As the roll *D* is not required to be of small diameter, and not required to hold all parts of the sheet for the operation of the beater, as is roll *c*, it can be made with teeth of much 25 greater length than could be used on the feed-roll *c*, and the teeth can be placed at greater distances apart, so that, except some extraordinarily large mass passes under it, the levers will not be affected by its action, and even 30 when such large mass does pass beneath it the fiber will be pushed forward by the teeth, and the pressure will somewhat relieve the pressure of the lever in contact with the cotton against the roll *c*, so that the roll will the more 35 readily nip and carry forward the mass, while it does not lose its control over the action of the evener-levers, nor its hold upon the cotton being operated upon.

By this construction I provide a machine 40 which will produce a more even and perfect lap than can be made upon any machine using only one of the two systems of evening the quantity of cotton fed to the beater, known as the "Lord" and "Kitson," and described in 45 Patents Nos. 52,008 and 222,410, because by the action of the gage-box mechanism, made substantially as hereinbefore described, and as described in Patent No. 222,410, the lumps and bunches are opened and any irregularities 50 in the sheet of fiber as it is fed to the "Lord" evener will be of such a nature that they will not require sudden changes in its feed to be made as do small lumps or bunches when they pass over the evener-levers, and which the even- 55 er by its method of operation and form of construction is not adapted to make; but if the sheet is more dense or thick in one part than in another it will become so more gradually, and when such parts pass over the evener-le- 60 vers there will be sufficient time during which the change is occurring to allow the evener-

levers to change the position of the belt to alter the speed of the feed-roll, which is not the case if small hard lumps be allowed to be fed to it, and which, without the action of the 65 gage-box mechanism, it is found practically impossible without previous beating to prevent.

When a greatly irregular sheet or one having many irregularities in its thickness in any given length is fed over the levers of a "Lord" 70 evener the action of the levers to shift the belt and alter the speed of the feed-roll is sudden; but as the parts possess considerable weight and the belt cannot be suddenly shifted on the cones, the effect is, first, to strain the machine 75 by a too sudden attempt to regulate and change the feed; and, second, as the thicker portion soon passes the feed-roll the change in feed will be made at the time a thin portion of the sheet has reached the roll, and consequently 80 a second irregularity in the quantity fed to the beater will be caused by the first. All these evils are prevented and avoided by my combination of gage-box with the evener.

By means of this combination and construc- 85 tion I obtain and produce results not possible for either the machines described in Patent No. 222,410 or 52,008 to produce separately, and that I have adapted the cotton-opener to the working of mixed fibers, such as cotton 90 and wool, and made it more perfect in its operation on dyed fibers, either of cotton or wool.

What I claim as new, and of my invention, is—

1. The combination of the gage-box *B* and 95 pressure-rolls *k* with the forwarding-roll *D*, evening-levers *C*, feed-roll *c*, and beater *G*, the gage-box, feed-roll, and evening-lever mechanism and beater being arranged so that the cotton passing to the beater passes through 100 the gage-box before coming into contact with the evener-levers and feed-roll, substantially as described.

2. The combination, with a feed-roll, a pressure-surface, which presses the cotton against 105 said roll, and a connecting and speed-changing mechanism between such pressure-surface and feed-roll, of a gage-box provided with grasping-rolls, breaker-shaft having fingers thereon, and an endless apron, substantially 110 as described.

3. The combination of the gage-box *B* and its mechanism, consisting of grasping-rolls, breaker-shaft, fingers, and an endless apron, with the evener-levers *C*, feed-roll *c*, and beater 115 *G*, the evener-levers and feed-roll being arranged in rear of the gage-box and in front of the beater, substantially as described.

RICHARD KITSON.
